DERRICK LEG FOOTING

Aaron D. Rhodes, Los Angeles, Calif., assignor
to Consolidated Steel Corp., Ltd., Los Angeles,
Calif., a corporation of California

Application July 29, 1938, Serial No. 221,947

5 Claims. (Cl. 189—21)

My invention relates to the construction of derrick towers and has particular reference to a derrick leg footing.

A derrick is used in the well drilling industry for handling the equipment for drilling the well, and in the case of deep wells, such as oil or gas wells, is called upon to support a load of many tons. This load gives rise to very great stresses in the derrick leg foundation, with the result that it is not unusual for a foundation to settle and throw a derrick out of vertical alignment. It then becomes necessary to jack up and shim under one or more legs to re-establish the vertical alignment.

Many schemes have been devised to provide a means for attaching the derrick leg to the foundation and make provision for jacking up the leg, but all have many disadvantages. Certain disadvantages, however, are common to most of the present derrick leg footings. For example, the footing members are usually attached to the derrick leg by means of bolts, with the result that all of the load on the leg must eventually, if not initially, be carried in shear in the bolts. This requires a number of very large bolts, with the result that the holes therefor in the leg seriously impair the bending strength of the leg. Devices of this type are also relatively expensive to install, inasmuch as all holes must either be drilled in the field at great cost or drilled in the shop with a great deal of clearance to assure a fit in the field and results in a possible serious impairment of the strength of the parts.

Derrick leg footings at present employed also have a disadvantage in that the lifting force of the jack which is used to lift the derrick leg must be transmitted from the footing member to the leg through some connecting means, usually bolts.

It is therefore an object of my invention to provide a derrick leg and footing assembly in which the footing and leg are formed together as an integral unit.

Another object of my invention is to provide a derrick leg footing in which the jack clip forming a part thereof is attached to the derrick leg in such a manner as to in no way impair the strength of either the footing member or the derrick leg.

It is also an object of my invention to provide a derrick leg footing of such type that said footing may be attached to the derrick leg without weakening the footing or the leg.

Another object of my invention is the provision of a derrick leg footing of such design that the footing may be permanently and securely attached to the lower end of the derrick leg while

in the shops, thus eliminating the relatively expensive operation of fitting and attaching at the erection site.

It is an additional object of my invention to provide a derrick leg footing of a design which will allow the formation of said footing and the lower portion of the derrick leg integrally with each other.

Other objects and advantages of my invention will become apparent from a consideration of the following description of the preferred embodiment of my invention, taken in connection with the accompanying drawing, in which:

Fig. 1 is a plan view of a portion of a derrick foundation showing the derrick leg footing of my invention in connection with the lower portion of a derrick leg and the derrick base ties and supports secured thereto.

Fig. 2 is a side elevation of the derrick and leg footing shown in Fig. 1.

As shown in Figs. 1 and 2, the base corner of a conventional derrick of this class includes a foundation pier 3, usually of concrete or other suitable material, upon which is placed a foundation leveling plate 4 which in turn usually supports the derrick leg 5. Perimetric members 6, usually of channel form, and diagonal braces 7 are also employed. In order that the derrick may operate as a unit structure for supporting the great loads which are applied, it is necessary that all of the aforementioned parts be securely attached to each other. In the present invention this is accomplished with my novel derrick leg footing in the following manner.

Footing side plates 8 are securely attached to, as by welding, or formed integrally with the derrick leg 5 and are allowed to extend beyond the edges of the leg to permit attachment of the perimetric members 6 as by bolts or other suitable fastenings 9.

Inasmuch as the derrick leg 5 does not extend vertically but slopes inward toward the center of the derrick tower and inasmuch as the assembly of floor joists and other structural members of the derrick base is facilitated if the sides of the perimetric members 6 are vertical, I have provided a slight twist in the footing side plates 8 so that one portion lies parallel to the derrick leg 5 and the extending portion lies parallel to the vertical side of the perimetric member 6.

In order to securely attach the diagonal brace 1 to the base corner unit I have provided a diagonal brace clip 10 which is secured to the footing side plates 8 as by welding, or which may be attached thereto by the same bolts 9 employed to

connect the perimetric base channels 6 to the side plates. The clip 10 extends between the projecting ends of the side plates 8 and behind the derrick leg 5. I have made the brace clip 10 of 5 such shape that the central portion thereof provides a flat surface against which an attachment plate 7a, welded upon the end of the diagonal brace 7, may abut and may be secured thereto as by bolts 11.

10 I have provided a footing plate 12 for the purpose of adapting the previously described unit assembly for resting on the foundation leveling plate 4. This footing plate 12 may be of almost any shape desired, but the form illustrated in 15 Fig. 1 is preferred for reasons to be set forth hereinafter. The footing plate 12 is securely attached to, as by welding, or is formed integrally with the derrick leg 5 and the footing side plates 8. The entire unit is then attached to the foundation as 20 by bolts 13 and nuts 13a embedded in the foundation 3 and extending upwardly through suitable holes in the plates 4 and 12.

While the advantages of this type of derrick legging in its inherent simplicity, strength and 25 rigidity have been outlined, the economies in manufacture resulting from this type of construction should not be overlooked. With this type of construction, the lower portion of the derrick leg and the parts forming the footing may 30 be fabricated in the shop to very close tolerances through the use of jigs, templates, and similar methods. While this same procedure may be used in the field, the accuracy of fabrication is 35 in question and the cost many times that of shop fabrication.

Should it be desired for any reason to raise one or more corners of the derrick, such adjustment is readily accomplished by raising the entire leg and leg footing and inserting shims of the proper thickness between the footing bottom plate 40 12 and the leveling plate 4.

In order to provide means for lifting the derrick leg after the derrick is erected, for the reasons outlined hereinbefore, I have provided a 45 jack clip 14 securely attached to or formed integrally with the derrick leg 5.

The jack clip 14 may be of any shape desired, but as illustrated is constructed in the form of a V shaped plate with the derrick leg angle 5 lying 50 inside the V and the apex of the V extending an appreciable distance from the corner of the leg. I propose to place the jack clip 14 the proper distance above the foundation plate 4 to allow a toe-jack resting thereon to be used to raise the leg by 55 engaging the toe of the jack with the under surface of the jack clip 14. As best shown in Fig. 1, I prefer to cut off that corner of the footing plate 12 which lies below the jack clip 14 to leave a clear space 15 on the foundation plate 4 for 60 accommodating the toe jack as indicated in dotted lines 16 in Fig. 2.

I have therefore provided a new and novel derrick leg footing which eliminates many of the disadvantages existing in the current methods 65 of construction and which will allow an appreciable reduction in the cost of fabrication and erection of derricks of this class. The construction I have described provides a stronger and more durable unit than any now available and will therefore reduce the cost of maintaining this class of derrick through the elimination of failures and excessive strains at this point.

In actual practice the employment of my derrick leg footing formed as a unit with the leg angle 5 facilitates the erection of the derrick in 75

the field by permitting the assembly on the ground of a complete section or panel representing the lower portion of one side of the derrick including a pair of adjacent legs and the girts and braces extending therebetween. Such assembly may 5 then be lifted in place and set upon the foundation piers with the footing bottom plates 12 resting in place upon the attachment bolts 13. The nuts 13a may then be quickly screwed down and that portion of the derrick side will be supported 10 solely by the bolts 13. This will permit the disconnection of the machinery employed to lift the assembled section in place and permit it to be used for lifting a section of the opposite side of the derrick into place.

15 When the bolts 13 for that side of the derrick are tightened, the erection machinery may then be disconnected and used to place the girt and bracing panels for the other two sides of the derrick, while the first two side sections are held 20 and supported solely by the bolts 13. This is permitted with my derrick leg and footing assembly by reason of the fact that all of the strains are transmitted directly between the derrick leg and the footing plates without exerting shearing 25 stresses upon a few bolts as is the case with separate footings merely bolted to the derrick legs.

Although I have illustrated and described a preferred embodiment of my invention, it is to be understood that changes in the details of construction and arrangement of parts may be made without departing from the spirit of the invention, and I do not wish to be limited except as defined in the appended claims.

I claim:

1. As an article of manufacture, an integral derrick leg unit comprising: a derrick leg portion terminating at one end in a footing plate integral with said leg portion and disposed transversely thereof; and a bracing plate integral with said 40 leg portion and said footing plate for bracing the junction between said leg portion and said footing plate.

2. As an article of manufacture, an integral derrick leg unit comprising: a derrick leg portion 45 terminating at one end in a footing plate welded to said leg portion as an integral unit therewith and disposed transversely thereof; and a bracing plate for bracing the junction between said leg portion and said footing plate, said bracing plate 50 being welded to said leg portion and to said footing plate to form an integral unit therewith.

3. As an article of manufacture, an integral derrick leg unit comprising: a derrick leg portion terminating at one end in a footing plate integral with said leg portion and disposed transversely thereof; and a plurality of bracing plates integral with said leg portion and said footing plate and disposed at angles relative to each other for bracing in a plurality of directions the junction between said leg portion and said footing plate.

4. As an article of manufacture, an integral derrick leg unit comprising: a derrick leg portion having an L shaped cross-section and terminating at one end in a footing plate integral with said leg portion and disposed at such an angle to said leg portion as to place said footing plate in a substantially horizontal position to act as a 70 footing member for said leg portion when said leg portion is installed on a derrick; and a pair of bracing plates integral with said leg portion and said footing plate, each of said bracing plates lying substantially in the plane of one of the 75

arms of said L shape for bracing the junction between said leg portion and said footing plate.

5. As an article of manufacture, an integral derrick leg unit comprising: a derrick leg portion having an L shaped cross-section and terminating at one end in a footing plate integral with said leg portion and disposed at such an angle to said leg portion as to place said footing plate in a substantially horizontal position to act as a

10 footing member for said leg portion when said leg portion is installed on a derrick; and a pair

of bracing plates integral with said leg portion and said footing plate, each of said bracing plates lying substantially in the plane of one of the arms of said L shape for bracing the junction between said leg portion and said footing plate, 5 and each of said bracing plates having portions disposed at right angles to the plane of said footing plate for attachment to perimetric members.
